UNITED STATES PATENT OFFICE

CECIL HARRY LAWRENCE, OF ATTLEBORO, MASSACHUSETTS, ASSIGNOR TO EVANS CASE COMPANY, OF NORTH ATTLEBORO, MASSACHUSETTS, A CORPORATION OF MASSACHUSETTS

DESIGN FOR A COMBINATION POCKET LIGHTER AND CIGARETTE HOLDER

Application filed October 19, 1929. Serial No. 33,101. Term of patent 7 years.

To all whom it may concern:

Be it known that I, CECIL HARRY LAWRENCE, a citizen of the United States, and a resident of Attleboro, in the county of Bristol and State of Massachusetts, have invented a new, original, and ornamental Design for a Combination Pocket Lighter and Cigarette Holder, of which the following is a specification, reference being had to the accompanying drawing, forming part thereof.

The figure is a perspective view of a combination pocket lighter and cigarette holder, showing my new design.

I claim:

The ornamental design for a combination pocket lighter and cigarette holder, as shown.

In testimony whereof, I have signed my name to this specification this 12th day of October, 1929.

CECIL HARRY LAWRENCE.
